UNITED STATES PATENT OFFICE.

ALBERT F. MADDEN, OF NEWARK, NEW JERSEY.

CYCLOMETER.

1,010,654.

Specification of Letters Patent.

Patented Dec. 5, 1911.

Application filed June 20, 1911. Serial No. 634,279.

To all whom it may concern:

Be it known that I, ALBERT F. MADDEN, a citizen of the United States, residing at Newark, county of Essex, and State of New Jersey, have invented certain new and useful Improvements in Cyclometers, of which the following is a full, clear, and exact description.

This invention relates to cyclometers or odometers for vehicles, and its chief object is to provide an improved mounting for the registering device, inclosing the same in a dust- and moisture-proof casing which can be conveniently mounted on a suitable part 15 of the wheel, for example on the hub in the manner of a hub cap.

A further object is to provide means for supporting the registering device inside the casing or housing in such manner as to permit the device to remain substantially stationary while the casing revolves around it.

To these and other ends the invention consists in the novel features of construction and combinations of elements hereinafter described.

The preferred embodiment of the invention is illustrated in the accompanying drawings, in which—

Figure 1 is a front view of the device, with the front of the casing broken away in part. Fig. 2 is a side view of the inner parts, the casing being in vertical section. Figs. 3, 4 and 5 are sections on lines 3—3, 4—4 and 5—5, respectively, looking in the direction of the arrows in each case.

The casing 10, in which the odometer is inclosed, is designed to conform to the general shape of the hub on which it is to be mounted, and is provided at its rear or inner end with a threaded flange 11 by which it may be rigidly attached to the correspondingly threaded hub, not shown. The rear wall 12 of the casing is integral therewith, and imperforate, so that by no possibility can dirt, moisture, or other foreign matter enter the casing from that direction. The front wall 13 is in the form of a disk screw-threaded in the front of the casing as shown, to form an hermetic joint therewith, and is provided with a central opening closed hermetically by a plate of glass 15, forming a window through which the centrally located odometer 16 can be easily observed and read. The odometer 16 is fastened to the rear wall 55 of an inner box or support 17 which is arranged concentrically to the casing 10 and

supported on the front and rear walls thereof by means of suitable ball bearings 18, 19, so as to permit the casing to revolve around the box with but slight friction. Extending upwardly from the odometer box is a lug 20 in which is pinned a shaft 21, parallel to the axis of the casing. On the ends of the shaft, pivoted thereon at their centers, are two arc-shaped depending arms 22, carrying on their ends an arc-shaped weight 23, the arms and weight together forming a circular element conforming to the cylindrical inner contour of the casing, but slightly smaller than the casing so as to leave a space between the two, as shown. The parts of this element are preferably integral with each other as shown. At the sides of the weight and below the horizontal diameter of the said circular element are suitable anti-friction devices, as the balls 24, to bear on the inner walls of the casing as the weight moves about the pivot 21. By reason of the weight the center of gravity of the combined weight, arms, odometer, and odometer box, is below the axis of the odometer support, namely the axis of the ball bearings 18, 19, said axis being indicated by the broken line 18^a. It will therefore be seen that the tendency of the parts named is to remain stationary in the position shown in the drawings, and that with the vehicle traveling on a smooth roadway the parts would in fact maintain such position with but little if any oscillation. It will also be observed that the weight is pivotally suspended, like a pendulum, from the shaft 21 considerably above the axis of the casing and the bearings of the odometer box, so that the weight can oscillate not only on the axis 18^a of the said bearings (the odometer box and other parts partaking of such movement) as a center of motion or oscillation, but can also oscillate on the pivot 21 as a center, the radius of its path when moving on the center 12 being considerably longer than the radius of the path about the center 18^a. Suppose now that the wheel carrying the cyclometer suddenly strikes an elevation or depression in the roadway, thereby converting part of the forward movement of the wheel into upward or downward movement, as the case may be. The weight 23, however, tends to continue its movement in the same line as before, and would, but for its suspension on pivot 21, swing more or less violently about the

center 18^a, and might even make one or more revolutions thereabout; but as the radius of swing about the pivot or center 21 is the longer, the weight swings on this axis instead of on 18^a and almost instantly comes up against the forward wall of the casing, rebounding to the rearward wall and oscillating in this manner until the impulse dies out. Ordinarily the impulse will be absorbed very quickly, but under exceptional circumstances may persist for a number of oscillations, but in no case will there be more than slight if any oscillation about the axis of the casing and the weight can never "turn turtle" or flop clear over from any motion of the vehicle. To damp the swing about the pivot 21 the latter is provided with one or more springs 25 extending forwardly and rearwardly under suitable pins 26 on the arms 22, so as to be flexed as the weight oscillates. These springs serve also to prevent movement about the pivot 21 when the vehicle is traveling on an ordinary smooth road, such as would cause only slight if any oscillation about the axis 18^a, and it is only on rough roads, such as would otherwise cause violent swinging on the axis 18^a, that the weight exerts sufficient force on the springs to flex them. It will therefore be seen that my improved device is not open to the objection heretofore urged against pendulously supported cyclometers, namely, the more or less extensive swinging to which they may at times be subject and which might interfere with proper actuation of the registering mechanism. On the contrary the oscillation in my device is necessarily very limited in extent and is too slight to have any appreciable effect on the operation of the odometer.

For the purpose of actuating the odometer 16 the shaft 30 of the latter is provided at one end with a ratchet 31 engaged above and below by two pawls 32, 33, mounted on the depending end of an L-shaped member or "wig-wag" 34 and held in engagement with the ratchet by light blade-springs 35. The horizontal portion of the wig-wag extends through an opening 36 in the lug 20 on the odometer box and is pivoted to the latter at 37. On the side edges of the depending portion of the oscillatory member or wig-wag are two wear plates 38, bearing on two cam rings 39, 40, fixed 55 on the front and rear walls of the casing and hence revolving therewith. These cams are alike in contour, but are arranged with the "low" portion of one opposite the "high" portion of the other, so that as they revolve 60 the member 34 will be swung on its pivot 37 first in one direction and then in the other, thereby reciprocating the pawls 32, 33. The swing of the member toward the left, as viewed in Fig. 2, retracts the pawl 32 and advances the pawl 33, and the right-

ward swing advances pawl 32 and retracts pawl 33, thus giving the ratchet two impulses in each complete oscillation of the actuating member. In the present case the cams are so designed as to give this member one complete oscillation, that is, an excursion in each direction, in each revolution of the casing, and this is sufficient to make the actuation of the odometer practically continuous, especially if the casing is revolving rapidly. It will of course be seen, however, that by suitable design of the cams the actuating member may be given any number of oscillations per revolution of the wheel, within certain limits determined by the inertia of the member, the increased wear on the plates as the rapidity of oscillation is increased, etc. The use of two pawls is also advantageous in that the retreating pawl serves as a brake, thereby preventing "over-run" of the ratchet by the momentum of the moving parts and hence obviating the use of special damping devices or the like.

The device herein specifically illustrated is merely the preferred form, and it is to be understood that the invention can be embodied in other forms without departure from its proper spirit and scope as defined by the appended claims.

I claim:

1. In a cyclometer, the combination of a closed casing adapted to be mounted on and revolve with a rotary element, an odometer support inside the casing and mounted to permit the casing to rotate around it, and a weight lying below the axis of rotation of the casing and pendulously supported on the odometer support above the said axis of rotation.

2. In a cyclometer, the combination of a closed casing adapted to be mounted on and revolve with a rotary element, and a support for an odometer inside the casing, mounted to permit the casing to rotate around it, said support carrying a pendulous weight lying below the axis of rotation of the casing and having a plurality of centers of oscillation.

3. In a cyclometer, the combination of a closed casing adapted to be mounted on and revolve with a rotary element, an odometer support inside the casing and mounted at the axis of rotation of the casing to permit the casing to rotate around it, a pivot on the odometer support above said axis, and a pendulous weight suspended on said pivot and lying below the said axis.

4. In a cyclometer, the combination of a closed casing adapted to be mounted on and revolve with a rotary element, an odometer supporting device inside the casing and mounted to permit the casing to revolve around it, a pendulous weight carried by the said device and capable of oscillation about a center above said axis, and means

for damping the oscillations of the weight about said center.

5. In a cyclometer, the combination of a closed casing adapted to be mounted on and 5 revolve with a rotary element, an odometer supporting element arranged inside the casing and having pivotal support whereby the casing may rotate around it, and means oscillatory about a center above the axis of rotation of the casing, to prevent oscillation of the odometer-supporting element about said axis.

6. In a cyclometer, the combination of a closed casing adapted to be mounted on and 15 revolve with a rotary element, an odometer support inside the casing, mounted to permit rotation of the casing around it and having a lug above the axis of rotation of the casing, and a pendulous weight suspended 20 from said lug and lying below said axis.

7. In a cyclometer, the combination of a closed casing adapted to be mounted on and revolve with a rotary element, an odometer support inside the casing and mounted to 25 permit the casing to rotate around it, and a pendulous arc-shaped weight arranged below the odometer support and suspended on the odometer support at a point above the axis of rotation of the casing.

30 8. In a cyclometer, the combination of a closed casing adapted to be mounted on and revolve with a rotary element, an odometer support inside the casing and mounted to permit the casing to rotate around it, a 35 weight pendulously mounted on the odometer support above the axis of rotation of the casing and lying below said axis, and yielding means for damping the oscillations of the weight.

40 9. In a cyclometer, the combination of a closed casing adapted to be mounted on and revolve with a rotary element, an odometer support inside the casing and mounted to permit the casing to rotate around it, said 45 support including a pendulous weight lying below the axis of rotation of the casing and having a plurality of centers of oscillation,

and odometer-actuating means inside the casing and operated by the rotary movement thereof.

50 10. In a cyclometer, the combination of a closed casing adapted to be mounted on and revolve with a rotary element, an odometer inside the casing and mounted to permit the casing to rotate around it, a ratchet associated with the odometer to actuate the same, pawls on opposite sides of the ratchet, an oscillating support for the pawls, and means actuated by rotation of the casing to oscillate the said support.

60 11. In a cyclometer, the combination of a closed casing adapted to be mounted on and revolve with a rotary element, an odometer inside the casing and mounted to permit the casing to rotate around it, a ratchet associated with the odometer to actuate the same, pawls on opposite sides of the ratchet, an oscillatory support for the pawls, a cam rotating with the casing and engaging the said support, and means for causing the support to follow the cam, whereby the support will 70 be oscillated and the pawls caused to actuate the ratchet in alternation.

75 12. In a cyclometer, the combination of a closed casing adapted to be mounted on and revolve with a rotary element, an odometer support inside the casing and mounted to permit the casing to rotate around it, an odometer mounted on said support, a ratchet associated with the odometer to actuate the 80 same, an oscillatory element pivoted on the odometer support, pawls carried by said element on opposite sides of the ratchet to actuate the same, a cam rotating with the casing and engaging the said element, and 85 means for causing the said element to follow the cam.

In testimony whereof I affix my signature in the presence of two subscribing witnesses.
